UNITED STATES PATENT OFFICE.

CHARLES BLESCH, OF NEWPORT, KENTUCKY, ASSIGNOR TO THE CRANE & BREED MANUFACTURING COMPANY, OF CINCINNATI, OHIO, A CORPORATION OF OHIO.

DESIGN FOR A BURIAL-CASKET HANDLE-PLATE.

43,186.

Specification for Design.

Patented Oct. 29, 1912.

Application filed April 21, 1911. Serial No. 622,630. Term of patent 7 years.

To all whom it may concern:

Be it known that I, CHARLES BLESCH, a citizen of the United States, residing at Newport, in the county of Campbell and State of Kentucky, have invented a new, original, and ornamental Design for Burial-Casket Handle-Plates, of which the following is a specification, reference being had to the accompanying drawing, forming a part thereof.

The figure is a front elevation of a burial-casket handle-plate, having a plane surface with a beveled or tapered edge and showing thereon a series of vertical stripes of equal

width running parallel to the opposite ends of said plate and extended entirely across the face of the plate with each alternate stripe an unbroken or plain one and each of the remaining stripes made up of parallel, closely-adjacent fine lines.

I claim:

The ornamental design for a burial-casket handle-plate, as shown and described.

CHARLES BLESCH.
